UNITED STATES PATENT OFFICE.

ANTON F. GROSS, OF ABERDEEN, WASHINGTON, ASSIGNOR TO JOE G. BATINOVICH, OF ABERDEEN, WASHINGTON.

CLUTCH-SPRING-COMPRESSING DEVICE FOR CHEVROLET AUTOMOBILES.

Application filed June 2, 1921. Serial No. 474,355.

To all whom it may concern:

Be it known that I, ANTON F. GROSS, a citizen of Poland, and resident of Aberdeen, in the county of Grays Harbor and State of Washington, have invented certain new and useful Improvements in Clutch-Spring-Compressing Devices for Chevrolet Automobiles, of which the following is a specification.

10 This invention relates to a clamp or tool for releasing the pressure of springs used in clutches of Chevrolet automobiles, the said device having for an object the provision of novel means for exerting pressure 15 for compressing the spring, in order that a pin which holds the spring on the shaft may be removed during repair work; and it is an object of this invention to provide anchoring means, associated with a yoke or 20 head shaped to bear against the spring and having a slot forming a clearance for the pin; the said device being effective to compress the spring and release the tension on the pin, as stated, in order that the pin may 25 be removed without injuring the parts of the device or preventing their dissociation, as would be the case if the spring were allowed to act.

An object of this invention is to provide 30 means by which the spring compressing element is adjustable and by which it may be held in different positions through the action of a screw by which the spring compressing element is moved with relation to the jaws.

A still further object of this invention is 35 to produce a clutch spring releasing member which can be readily applied to or removed from the shaft having the spring with which it coacts, and in which an adjustment is provided to allow for variations in sizes or the like.

With the foregoing and other objects in 40 view, the invention consists in the details of construction, and in the arrangement and combination of parts to be hereinafter more fully set forth and claimed.

In describing the invention in detail, reference will be had to the accompanying 45 drawings forming part of this application wherein like characters denote corresponding parts in the several views, and in which—

Figure 1 illustrates a view in elevation

of a clutch spring releasing device embodying the invention; 55

Figure 2 illustrates a similar view at a position at right angles to that shown in Fig. 1; and

Figure 3 illustrates an underneath plan 60 view thereof.

In these drawings 5 denotes a head having a screw threaded aperture 6, the said head terminating in an arm 7 which is of curved formation, as shown, the said arm having an inturned end terminating in proximity to a line through the longitudinal axis of the aperture 6 and having diverging jaws 8 and 9 formed thereon, the outer edge of which is curved, as shown 70 at 10. The head 5 has an arm 11 connected to it through the medium of a pivot 12, and the said arm has an inwardly turned end terminating in the jaws 12' and 13, similar in construction to the jaws 8 and 9 75 and intended to coact therewith during the operation of the device.

A screw 14 is threaded through the aperture 6 of the head and it is provided with a head 15 and a suitable operating handle 80 16 by which the screw is turned, the said screw having a yoke 17 swiveled on its end between the arms. The configuration of the yoke is such that it will bear against the end of the clutch spring of the Chevrolet 85 automobile, and the jaws of the arms embrace the shaft in which the spring is seated, so that when the screw is threaded to advance through the head, it will result in compressing the spring of the clutch to 90 relieve its tension from the pin, in order that the same may be removed to disassemble this part of the automobile.

A spring 18 has one end anchored to the arm 7 and the opposite end anchored to the 95 arm 11, and the said spring 18 is operative to normally exert a pull on the arm 11 to hold the jaws in operative relation to each other.

The yoke 17 has a pin 19 projecting from 100 it on which a yoke brace 20 is oscillatable, the said yoke brace having an angularly disposed end 21 partially embracing the arm 11 for holding the movable arm in adjusted position with relation to the arm 105 7 while the device is being operated to compress a spring. From an inspection of the drawing, it will be seen that when the

arm 11 is moved into cooperative relation with the arm 7, the yoke may be oscillated on its pivot to cause the angularly disposed end 21 to bear against it after the jaw of the arm 11 is properly seated with relation to the element with which it coacts while the screw is being advanced, and of course this relation of parts prevents any disarrangement of the parts which might interfere with the successful operation of the device.

I claim:

1. In a clutch spring compression device for automobiles, a head having a rigid and a pivoted arm, each having an inturned end terminating in a jaw, one of which coacts with the other, a yoke, means for advancing the yoke with relation to the jaws of the arms, and means for holding the pivoted

arm in operative relation to the rigid arm 20 and the yoke.

2. In a clutch spring compression device for automobiles, a head having a rigid arm and a pivoted arm, the said arms having inturned ends terminating in jaws, the said head having a threaded aperture therein, a screw threaded in the aperture of the head, a yoke swiveled on the inner end of the screw, said yoke having a slot therein to form a clearance for a clutch spring pin 30 and the said yoke being adapted to bear against the end of said spring, a yoke brace pivoted to said yoke and having an extension partially embracing and bearing on the pivoted arm for retaining the parts 35 in operative relation to one another.

ANTON F. GROSS.
